UNITED STATES PATENT OFFICE.

ALONZO W. EPRIGHT, OF ALTOONA, PENNSYLVANIA.

RAILWAY TRACK-SCALE.

1,296,274.

Specification of Letters Patent.

Patented Mar. 4, 1919.

Application filed March 29, 1918. Serial No. 225,429.

To all whom it may concern:

Be it known that I, ALONZO W. EPRIGHT, a citizen of the United States of America, and resident of Altoona, in the county of Blair and State of Pennsylvania, have invented a certain new and useful Improvement in Railway Track-Scales, of which the following is a true and exact description, reference being had to the accompanying drawings, which form a part thereof.

My invention relates to weighing scales, and particularly to weighing scales of large capacity, such as railway track scales, and the primary object of the invention is to prepare a simple and easily adjustable suspension bearing connection between the platform or bridge of the scale and the scale levers.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of my invention.

Figure 1 is a sectional elevation, with parts broken away and removed, of a railway track scale.

Fig. 2 is a side elevation of a portion of the mechanism shown in Fig. 1, and

Fig. 3 is an elevation taken similarly to Fig. 1, showing a portion of the apparatus shown in Figs. 1 and 2.

The railway track scale, in which I have shown my invention embodied in the drawings, comprises a rigid bridge element comprising main longitudinal beams A, cross ties B, chairs C, and track rails D carried by the chairs C. The chairs C project through the stationary platform E, which forms the roof of the scale pit.

The bridge is supported by the main scale levers O through connections which comprise a main bearing member H for each lever O. The main bearing member H is in the form of an inverted U with its base channelled to receive and be bolted to the under side of the corresponding bridge beam A. The lower ends of the legs H' of the U shaped bearing member H, are formed with slotted bearings H² for a cross bar I. The cross bar I passes through a pair of links J, by which the cross bar and its load

are supported. The upper ends of the links are hooked over an equalizing member K. The member K comprises two similar side members and a central connecting portion K', which has a swivel bearing on the upper side of the knife edge bearing block support L. The lower edge of the latter rests upon the knife edge M, carried by the corresponding main scale lever O. The latter is provided with a knife edge bearing O' resting on bearing blocks, carried by a supporting bracket or stand P. The long arm of each main lever O is connected by links and the usual knife edge bearings to a secondary lever Q.

With the construction described desirable uniformity in the pressure imposed on the knife edge bearings of each main lever O makes highly desirable a simple and effective adjustment between each leg H' of each main bearing member H and the corresponding end of the corresponding cross bar I, so that each end of each cross bar may be adjusted toward and away from the bridge beam A above it. This adjustment is obtained, in accordance with the present invention, by providing a bearing in each slotted leg H' of the casting H for a sliding wedge member R extending transversely to the cross bar. Each wedge member R is formed at one end with a threaded extension R', which passes through a bracket H³ formed integrally with the bearing casting H. Nuts R², screwed on the threaded extension R', and bearing against opposite sides of the bracket H³, form a means for adjusting the bar R lengthwise, and for securing it in any desired adjustment. Preferably, as shown, the ends of the cross bar I are notched, as indicated at I', to receive the bars R. The bottoms of these notches are inclined to correspond to the wedge taper of the corresponding member R. With the simple construction described, positive and accurate adjustment of the ends of each cross bar, relative to the corresponding main bearing member H may be easily secured, and there is nothing about this adjustment liable to get out of order or to fail under the heavy load put upon it.

Having now described my invention, what I claim as new and desire to secure by Letters Patent, is:

1. In a suspension bearing for a weighing scale, the combination of a main bearing member in the form of an inverted U, hav-

ing slotted bearings in its legs, a cross bar having its ends received in said slotted bearings, and a wedge member transverse to the bar, slidingly mounted in said main bearing member and interposed between the latter and one end of the cross bar.

2. In a suspension bearing for a weighing scale, the combination of a main bearing member in the form of an inverted **U** having

10 slotted bearings in its legs, a cross bar having its ends received in said slotted bearings, a pair of wedge members transverse to the bar, one slidingly mounted in each leg of said main bearing member and interposed 15 between the latter and the corresponding end of the cross bar, and a threaded connection between said wedge and said main bearing member for adjusting the wedge in the direction of its length.

20 3. In a weighing scale the combination with the scale bridge and its main supporting levers, of suspension bearing connections between the bridge and levers, each comprising a main bearing member in the form 25 of an inverted **U**, having its base secured to the bridge and having slotted bearings in

its legs, a cross bar having its ends received in said slotted bearings, means including links encircling said cross bar for suspending the main bearing member and its portion 30 of the bridge load from the corresponding lever, and an adjusting wedge bar mounted in said main bearing member and interposed between the latter and one end of the cross bar.

35 4. In a weighing scale the combination with the scale bridge and its main supporting levers, of suspension bearing connections between the bridge and levers, each comprising a main bearing member in the form 40 of an inverted **U**, having its base secured to the bridge and having slotted bearings in its legs, a cross bar having its ends received in said slotted bearings, means including links encircling said cross bar for suspending 45 the main bearing member and its portion of the bridge load from the main lever and adjusting wedges slidingly mounted in said main bearing member and interposed one between the latter and each end of the 50 cross bar.

ALONZO W. EPRIGHT.
